(57) **CLAIM**

The ornamental design for a hand washing station, as shown and described.

DESCRIPTION

FIG. 1 is a perspective view of a hand washing station showing the new design;

FIG. 2 is a front elevational of the hand washing station seen in FIG. 1;

FIG. 3 is a back elevational view of the hand washing station seen in FIG. 1;

FIG. 4 is a right side elevational view of the hand washing station seen in FIG. 1, the left side elevational view being a mirror image thereof;

FIG. 5 is a top plan view of the hand washing station seen in FIG. 1; and,

FIG. 6 is a bottom plan view of the hand washing station seen in FIG. 1.

In the drawings, the broken lines depict portions of the hand washing station that form no part of the claimed design.
